UNITED STATES PATENT OFFICE.

FRANKLIN G. HOBART AND WALTER E. REULING, OF BELOIT, WISCONSIN, ASSIGNEES
TO FAIRBANKS, MORSE & CO., OF CHICAGO, ILLINOIS, A CORPORATION OF ILLINOIS.

FEED-GRINDER.

9,35,985.

Specification of Letters Patent.

Patented Oct. 5, 1909.

Application filed April 17, 1908. Serial No. 427,762.

To all whom it may concern:

Be it known that we, FRANKLIN G. HOBART and WALTER E. REULING, citizens of the United States, residing at Beloit, Rock county, Wisconsin, have invented certain new and useful Improvements in Feed-Grinders, of which the following is a specification.

Our invention relates to feed grinders, especially those intended to grind corn on the cob, and the object of the invention is to provide certain novel features of construction whereby the efficiency and durability of the grinder is increased.

One of the features of novelty in our grinder is the mechanism for controlling the feed opening between the cob crusher part and the grinding disks.

Another novel feature is the means for holding the grinding disks out of contact with each other when there is no material being ground between them.

Other novel features are the means by which the disks are permitted to move apart in case any stone, piece of metal or other obstruction should come between them; also the construction of the case inclosing the grinding disks and parts immediately associated therewith.

We obtain our objects by the mechanism illustrated in the accompanying drawings, in which:

Figure 1 is a side elevation of the assembled machine excepting the legs or supporting framework. Fig. 2 is a sectional elevation taken lengthwise of the shaft. The plane of the figure is indicated by the line 2-2 Fig. 1. Fig. 3 is an end elevation looking from the grinding end of the machine. Figs. 4, 5, 6, 7 and 8 are sections taken respectively on the lines 4-4, 5-5, 6-6, 7-7 and 8-8 of Fig. 2. Fig. 9 is a perspective view of one of the breakers. Fig. 10 is a side view of the end breaker in its preferred form. Fig. 11 is a detail sectional view taken horizontally through the center of the bearing remote from the grinders showing how it receives the lateral thrust of the breakers due to the spreader spring 50. Fig. 12 is a vertical sectional view of the end thrust bearing for the main shaft.

Similar numerals refer to similar parts throughout the several views.

The supporting standard 20 is constructed

according to any suitable design and carries 55 the hopper 21 and the bed plate 22 in which the preliminary crushing takes place. In the preferred instance the end plate 23 is bolted to said bed plate and these plates carry the bearings 24 and 25 respectively, wherein the 60 main shaft 26 is journaled. Said shaft is both rotatable and slidable within its bearings and is driven by the band wheel 27 or other suitable means. In the preferred construction a pin 28 extends through the shaft 65 and into a recess 29 formed in the end of the hub of wheel 27 as shown in Fig. 2. A coiled compression spring 30 is interposed between the inner end of the hub and the bearing 24, as a result of which the shaft is, 70 to a limited extent, slidable relatively thereto.

Arranged upon the shaft within the concave lower portion of the bed plate 22 are breakers 31 and 32 shown separately in Figs. 9 and 10 respectively, and shown in section 75 in Fig. 2. Breaker 32 is preferably of special form, being provided with a helical flight 32^a and located near the end of the hopper remote from the disks for keeping this portion of the hopper and bed plate clear and 80 forwarding the cobs toward the disks. In the preferred form, shown in Figs. 2 and 5, breaker 32 has a recess 32^b adapted to receive the pin 33 in such manner that the breaker rotates with the shaft but is longitudinally 85 movable relatively thereto for a limited distance. If desired, pin 33 may be made of wood or other breakable material so as to break before the machine wrecks itself in case an obstruction is encountered. Breakers 90 31 and 32 are adapted to interlock one with another in such manner that they may be slipped over the shaft separately but, commencing with breaker 32, each will drive the next one to it. The teeth of said breakers 95 are arranged spirally so that they will not only crush the cobs but will tend to forward them to the space between the grinding disks.

It is desirable that a cutting chamber 36 be provided beyond the breakers 31 to cooperate with cutter 37 which interlocks with the breakers 31 so as to rotate therewith and with shaft 26, the parts being clearly shown in Figs. 2 and 3. A stationary grinding disk 38 is bolted or otherwise rigidly secured 100 to bed plate 22 and has an aperture 39 through which material may enter the space between the grinding disks. In the pre-

ferred form this aperture 39 is segmental in outline as shown in Fig. 8. The amount of opening through the stationary grinding disk is regulated by means of a gate 40 located adjacent to the disk 38 and which is rotatable about shaft 26 as a center. Said gate has an aperture which by preference is similar in size and outline to the aperture 39 in the stationary grinding disk. The parts are so arranged that when the gate 40 is rotated it will vary the size of the opening into, said stationary grinder. Said gate is provided with an extension 41 whereby it may be rotated, said extension having a return bend 42 adapted to engage the flange 43 of the cutting chamber 36 as clearly shown in Fig. 1. Said extension and return bend are apertured to receive a bolt 44 having a wing nut 45 thereon and the parts are so arranged that when said nut is tightened it will cause the extension 41 and bend 42 to clamp the flange 43 and hold the gate in set position. By this means the size of opening into the grinding disk may be regulated to a nicety by moving but a single member of the machine and the part may be set by merely screwing up the single nut.

Opposed to the stationary grinding disk is a rotary grinding disk 46 which is bolted or otherwise secured to the spider 47 which rotates with shaft 26. The preferred means of attachment of spider 47 to shaft 26 is pin 48, shown in Figs. 2 and 4. As the connection is thus rigid the spider and rotary grinder not only rotate with shaft 26 but produce a longitudinal movement of said shaft in case the rotary grinding disk moves toward or from the stationary grinding disk. In order to permit such motion toward and from the stationary grinding disk there is, under normal conditions, a space between the hub 49 of spider 47 and the inside of end plate 23 as clearly shown in Fig. 2.

A coiled compression spring 50 encircles shaft 26 and is located between the two grinding disks for keeping the latter apart when no material is in the space between them. In the preferred arrangement spring 50 bears at one end against the hub 49 of the spider 47 and at the other end against the cutter or breaker 37. The thrust thus set up in part 37 is transmitted through the breakers 31 to the breaker 32 which bears against the end of box or bearing 24. This keeps parts 37, 31 and 32 always in interlocked position and yet permits the longitudinal movement of the shaft when the grinding disks vary their distance from each other.

In order to permit the rotary disk to yield when an obstruction is present and yet normally hold the disk as close as it should be to the stationary disk, an arm 51 is pivoted to a rib or boss 52 formed upon the end plate 23, the free end of said arm being

yieldingly connected to the end plate 23 by a tension spring 53 best shown in Fig. 1. The inward movement of arm 51 is limited by a stop 54 which contacts a suitable portion of said end plate. Pressure is transmitted from arm 51 to shaft 26 through the regulating screw 55 which screws into said lever in such position that its inner end contacts a thrust bearing which in its preferred form consists of a block 56, recessed to fit over the end of the shaft 26 and convey oil thereto through a duct 56^a leading downward from the oil reservoir 56^b as best shown in Figs. 2 and 12. It is desirable to interpose one or more anti-friction disks 56^c between the block and the end of the shaft. Screw 55 is rotated by a hand wheel 57, this wheel being held in set position by means of a dog 58 adapted to enter suitable notches formed in said hand wheel as best shown in Figs. 2 and 3. When an obstruction enters between the grinding disks it will cause the rotary disk to move away from the stationary disk, carrying the shaft 26 with it and stretching spring 53. As soon as the obstruction has passed out the spring 53 will return the parts to normal position with the stop 54 in contact with the end plate 23. The distance between the disks when in approached position may be regulated by rotating the hand wheel 57 and thus increasing or decreasing the pressure upon spring 50, spring 53 being strong enough to hold stop 54 in contact with end plate 23 except when a stone or other substantially non crushable object comes between the disks.

In order to provide motive power for the operation of supplementary mechanism such as an elevator (not shown) it is desirable to spline a sprocket wheel 60 upon shaft 26 between bearing 25 and arm 51, such connection permitting longitudinal movement of shaft 26.

The formation of the case which incloses the grinding disks is of special convenience in our machine, its construction being best shown in Figs. 1, 2 and 4. The cover 61 consists, preferably of sheet steel and is arched so as to come outside of and concentric with the grinding disks. It is substantially semi circular in cross section and is provided at its lower edges with flanges 62 which bear upon the bed plate 22 and are apertured for receive cap screws 63 (shown in Fig. 1). The bottom of the case is formed by the main frame itself which comes approximately to the level of the center of the disks. The end plate 23 which bolts to the main frame forms the end of the case and completes the closure about the disks. With this construction the disks are readily accessible and may be removed by merely unbolting the end plate and removing the pin 48.

Having thus described our invention, what

we claim as new and desire to secure by Letters Patent, is:

1. In a feed grinder, a stationary frame provided with a concave, a shaft journaled in said frame, a rotary grinding disk rigidly secured to said shaft, a stationary grinding disk rigidly secured to said frame and adapted to coöperate with the rotary grinding disk, a set of interlocking breakers on said shaft in position to coöperate with the concave, the end breaker having a longitudinal recess therein, a pin in the shaft adapted to enter the recess in said end breaker for rotating the same, a journal bearing in the frame adapted to contact with said recessed breaker for holding it against longitudinal movement on the shaft in one direction, a spring interposed between the rotary grinding disk and the other end breaker for holding said breakers in locked engagement, and means for adjusting said shaft relatively to its support to thereby increase or decrease the strain on said spring.
2. In a feed grinder, a stationary frame provided with a concave, a shaft journaled

in said frame, a rotary grinding disk rigidly secured to said shaft, a stationary grinding disk rigidly secured to said frame and adapted to coöperate with the rotary grinding disk, a set of interlocking breakers on said shaft in 30 position to coöperate with the concave, the end breaker having a longitudinal recess therein, a pin in the shaft adapted to enter the recess in said end breaker for rotating the same, a journal bearing in the frame 35 adapted to contact with said recessed breaker for holding it against longitudinal movement on the shaft in one direction, a spring interposed between the rotary grinding disk and the other end breaker for holding 40 said breakers in locked engagement, and means coöperating with the shaft for holding said grinding disk in contact with said spring to thereby keep said breakers in locked engagement.
